2,685,391

METHOD AND APPARATUS FOR MAKING
FUR COATS

Richford A. Thomas, Flint, Mich.

Application January 5, 1952, Serial No. 265,081

10 Claims. (Cl. 223—68)

1

This invention relates in general to the making of fur coats, and in particular, to a novel and improved method of and an apparatus for reconstructing fur coats which eliminate considerable time-consuming operations and produce better constructed, perfectly fitted, and correctly styled coats that hang properly. The present invention is in the nature of an improvement of my Patent Number 2,313,374, granted March 9, 1943, Apparatus for Reconstructing Fur Coats.

In the above-patented apparatus, there is disclosed an open front form over which a wetted fur coat, minus the lining, collar, and sleeves and with the skin side of the fur next to the form, is held by a pair of movable stretcher boards during drying for shrinking the skins to the shape of the form, said stretcher boards being located in the open front of the form. Attachable to the form are kyle strips and presser plates over which and under which, respectively, the skirt portion of the coat is adapted to be supported during drying for providing flares in the coat. Such a method and apparatus eliminate the use of patterns for each part of a coat when restyling a coat, and consequently do not require the ripping of the coat into pattern parts and the tacking and shrinking of each pattern part separately in order for them to lie flat while being cut according to a pattern. Dispensing with the use of patterns also obviates taping all edges of shrunken pattern parts of the coat prior to the sewing of the pattern parts together as well as the destructive process of pounding seams which attach the shrunken pattern parts together to make the different pattern parts blend together smoothly.

The present invention provides certain improvements in the method of association of fur coats relative to the form, there being provision for placing the coat on the form wrong side out or, in other words, with the fur side next to the form and the skin side and seams exposed, both during marking of pieces of the fur which are to be removed from the coat and other markings at places where pieces are to be added in accordance with alterations to be made to the coat to fit the form, and during the shrinking of the skins of the fur to the shape of the form.

Approximately ninety per cent of all types of furs from which coats are made are of a character that lend themselves for placement on forms with the work side of the furs out where it is accessible for work thereon. The other ten per cent of coats are of a silky, tightly curled

2

type of fur, such as Persian lamb. These can be successfully remodeled on the apparatus, but due to the fact that pressure on and lack of air to the fur when shrunk kills the silky lustre, this type of fur is placed on the form with the fur side out while the shrinking operation is performed.

It is therefore the main object of the present invention to provide a fur coat form having a sectional portion thereof removable and substitutable with other sectional portions of different constructions in accordance with the manner of association of the fur relative to the form for directing fullness, such as flares, in proper directions and for varying the number as well as design and location of flares to be blocked in the coat.

Another object of the invention is to provide a coat form upon and to the shape of which a wetted fur coat is adapted to be shrunk, said form having recesses therein for receiving and supporting inwardly directed kyles under which the fur of the coat is supported during drying for blocking fullness in the coat.

25 A further object of the invention is to provide a fur coat form having expandable sectional sleeve units that are removable from the body portion of the form for permitting placing of a fur coat with the sleeves thereon over the form prior to inserting the sectional sleeve units in place and thereby permitting the marking for removal and/or addition of pieces of fur and also permitting, at a single wetting period, the shrinking of the skins of the fur over both the body and the sleeves as well as the material at the seams 35 which attach the sleeves to the body.

It is also an object of the invention to provide an apparatus of the above-indicated character which is substantial in construction, economical to manufacture, and thoroughly efficient and practical in use.

These, together with various auxiliary features and objects of the invention which will later become apparent as the following description proceeds, are attained by the present invention, a preferred embodiment of which has been illustrated, by way of example only, in the accompanying drawings, wherein:

Figure 1 is a rear elevation of the improved apparatus showing a fur coat thereon;

Figure 2 is a side elevation of the same;

Figure 3 is a horizontal section taken on line 3—3 of Figure 1;

Figure 4 is a fragmentary transverse section 55 on line 4—4 of Figure 2;

Figure 5 is a vertical section taken substantially on lines 5—5 of Figures 1 and 3;

Figure 6 is a perspective view of a removable section of the back of the body portion of the form used when remodeling coats to have two flares down the backs thereof and is shown as being used in Figures 1 and 3;

Figure 7 is a perspective view of one of the kyles used with the back section shown in Figure 6;

Figure 8 is a side elevation of the upper portion of the apparatus with the sleeve form portion removed and with the clamping arm swung to inoperative position and broken away;

Figure 9 is a perspective view similar to Figure 6 showing the back section which is used when remodeling a coat having a plain back; and

Figure 10 is also a similar perspective view showing the back section used when remodeling coats to have four flares down the backs thereof.

Referring now more specifically to the accompanying drawings wherein like numerals designate similar parts throughout the various views, the numeral 15 indicates a hollow open front body portion of a coat form constructed of wood, papier-mâché, or similar material, waterproofed, of substantial construction, and comprising a bottom wall 16 and a solid reduced neck portion 17. Within the hollow form 15 substantially centrally thereof and extending through the bottom wall 16 and into a floor stand 18 supporting the form 15 is the lower end of a vertical rod 19 that extends the entire height of the form with the upper end projecting through the solid neck portion 17. The rod 19 is also supported in the center of the hollow form 15 and is held against turning and end movement relative thereto by two sets of arm brackets 20 that engage around the rod 19 and are secured to a pair of vertical longitudinally extending reinforcing strips 21 along opposite sides of a relatively large back opening 22, as shown in Figures 3 and 5.

As disclosed in my patent referred to above, there is provided at the open front, designated by the numeral 23, a pair of adjustable stretcher boards 24 and 25 that extend from the bottom wall 16 to the bust area of the form. The boards 24 and 25 are carried by a plurality of arms 26 pivotally supported on the rod 19 and are moved toward and away from one another by shafts 27 threadedly connected to the arms 26 of both boards and rotated by worm gearing 28 from a vertically extending shaft 29 with a crank handle 30 on an end projecting below the bottom wall 16. The shafts 27 have their opposite ends threaded in opposite directions for feeding the stretcher boards to and away from overlapping positions according to the direction of rotation of said shafts. It is to the inner sides of the stretcher boards adjacent their forward longitudinal edge portions that the front margins of the coat are tacked for stretching the coat tightly upon the form.

The opening 22 in the back of the body portion of the form 15 is substantially rectangular in shape, is of a size to include practically the entire back, and is adapted to receive any one of a number of differently constructed back sections according to the style to which the coat is to be remodeled on the form. For purpose of illustration, there is shown in the opening 22 and attached in place on the form 15, as in Figures 1, 2, 3, 5, and 8, a back section 31 used in reconstructing a coat which will have two flares starting from below the shoulders and

extending downwardly the full length of the back of the coat, this back section 31 being shown separately in Figure 6. The back section 31 is joined flush with the outer surface curvature of the form 15 and rests at its vertical longitudinal side edges against portions of the reinforcing strips 21 that project slightly into the opening 22, as shown best in Figure 3. Along and extending above the top edge of the back section 31 and set inwardly the thickness of the wall of the form 15 is a retaining flange 32 that engages behind the wall of the form at the top edge of the opening 22 for holding the upper portion of the back section against outward movement. On the lower end of the back section 31 and adapted to project into the form 15 and to rest on top of the bottom wall 16 of the form is substantially right-angled plate 33, which is provided with a hole 34 therein into which a manually operated plunger 35 carried by the bottom plate 16 engages for holding the lower portion of the back section against outward movement.

In the contoured wall of the back section 31 and extending the major portion of its height is a pair of spaced, isosceles triangular-shaped recesses 36 bounded by extremely long sides 37 that round into the outer surface of the back section and by short and flat base sides 38 arranged on the same horizontal plane as the upper surface of the plate 33. Received in each of the recesses 36 and projecting into the hollow body form 15 is a kyle or flare forming member 39 substantially V-shaped in cross section and diminishing in size as it extends upwardly which comprises a pair of flat tapering walls 40 that are gradually rounded together along their connecting side portions, as at 41. The lower larger ends of the walls 40 are joined by a cross wall 42 adapted to be seated on the upper side of the plate 33 of the sectional back, there being a peg 43 projecting downwardly from the cross wall 42 for reception into either one of a pair of spaced holes 44 provided in the plate 33, said pair of holes providing for adjustment of the depth of protrusion of the flare forming member into the sectional back. While the flare forming members 39 are shown and described as being of shell-like construction with an open back, it is to be understood that such members may be made solid and triangular shape in horizontal cross section.

On the end of the rod 19 above the neck portion 17 of the body form 15 is supported a rearwardly directed bar 45 to which is pivotally connected, as at 46, one end of a clamping arm 47 that has secured on its free end a transversely arranged curved plate 48 that engages the upper portions of both flare forming members 39 for holding said members in proper positions in the recesses 36. A pair of coil springs 49 are connected to the bar 45 and the arm 47 for applying pressure to the arm to hold the flare forming member in place as shown in Figures 1, 2, and 5, and for supporting the arm in an out-of-the-way position when the clamping structure is not in use, as shown in Figure 8.

In Figures 9 and 10 are illustrated back sections 31^a and 31^b to be substituted for the back section 31 when reconstructing fur coats to styles without ripple backs and with backs having four flares, respectively, there being four kyles or flare forming members of the same construction as that previously described and of proper size and shape for use in the recesses 36^b of the back section 31^b shown in Figure 10.

To opposite sides of the body form 15 at the shoulder area thereof are attached, by screws 50, flat; oval-shaped plates 51, each provided with two pairs of bayonet slots 52 and 53; the slots of each pair being in alignment one above another, being of different lengths, and having the enlarged slot portions 54 thereof at opposite ends. It is to these plates and through the bayonet slots thereof that sectional sleeve forms 55 are detachably connected. Each sectional sleeve form 55 is composed of three longitudinally extending flat board sections 56, 57, and 58 arranged edge to edge. The intermediate section 57 is tongue-and-grooved to the outer sections 56 and 58, as at 59, for endwise sliding movement thereof relative to said outer section, there being a pivoted retention member 60 on the lower end of the section 58 adapted to be swung under the intermediate section 57 for holding the same against downward sliding movement.

Near the upper end and from the underside of each outer sleeve section 56 and 58, the headed ends of a pair of screws 61 project a distance equal to the thickness of the plates 51 for engaging into the bayonet slots 52 and 53 to connect said section to the body form 15. As shown in dotted lines in Figure 2, the screws 61 on each outer section are spaced apart a distance relative to lengths and arrangement of the bayonet slots of each pair. This arrangement permits the insertion of the heads of the lower screws into the lower ends of the lower slots and then the movement of the sleeve sections upwardly and the insertion of the heads of the upper screws in the upper ends of the shorter upper slots. The shorter upper slots will prevent the lowering of the sleeve sections to positions that would permit the heads of the lower screws to become disengaged from the lower slots. The outer sleeve sections 56 and 58 may be of different widths and outer marginal contours according to the size and style of sleeves to be reconstructed on the sleeve forms; and by having intermediate slidably removable section 57 which expands the outer sections 56 and 58 to proper sleeve forming positions, it is possible to stretch sleeves on the form with cuff areas of smaller widths than other portions of the sleeves.

In reconstructing a fur coat with the improved apparatus after taking out the lining and padding and removing the collar, pocketing, buttons, loops, etc., the coat is placed on the body form 15 wrong side out with both sectional sleeve forms 55 removed and the back section 31, 31^a, or 31^b in place according to the style of back the coat is to have when remodeled. Should either of the back sections 31 or 31^b be used, and there appears to be adequate material in the coat, the flare forming members 39 are inserted in the recesses 36 or 36^b forcing fullness in the coat to extend thereunder and into the hollow interior of the body form 15 while conforming to the shape of said members. However, should there not appear to be sufficient material in the coat to fit around the body form and provide for any flares that are to be formed therein, the locations and sizes of inserts are marked on the skin side of the fur; the coat is removed from the form; and the necessary pieces of fur are added before returning the coat to the form. The coat is then drawn as smoothly as is possible over the body form and is temporarily tacked at the front to hold the coat in position on the body form.

With the fur side next to the body form and the skin side and seams exposed, markings of small pieces of the fur which are to be removed from the coat and other markings at places where small

pieces are to be added are made on the skin side in accordance with slight alterations to be made to the body of the coat to fit to the contour of the body form.

The sectional sleeve forms 55 are then connected to the shoulder plates 51 by first inserting the outer sections 56 and 58 upwardly in the sleeves and engaging the heads of the screws 61 in the slots 52 and 53. After the outer sleeve sections are securely connected, the intermediate sleeve sections 57 are slid upwardly in the sleeves with the tongues thereon engaging into the grooves of the outer sections 56 and 58 and are held in place by the pivoted retention member 60. The sleeves of the coat are then marked according to the removal of pieces of fur to fit the sleeves of the coat to the sectional sleeve forms 55. Should the sleeves of the coat not have sufficient material therein to permit the insertion of the intermediate sections 57, additions must be made to the sleeves before fitting them to the shape of the sectional sleeve forms.

After all markings have been completed, the coat is removed from the apparatus and is altered 25 according to the markings thereon, it being unnecessary to tape the edges before sewing the seams or to pound the seams in order to make them lay flat and smooth, as the coat has not as yet been wetted and shrunk. The skin side of the 30 coat is wetted before returning it to the form with the skin side out and before arranging the flare forming members 39 and sectional sleeve forms 55 in place. With the stretcher boards 24 and 25 in open position, the front marginal edges 35 of the coat are tacked to the stretcher boards for drawing the coat tight about the form upon movement of said stretcher boards to proper overlapped position. By having the skin side of the coat exposed, additional moisture may be 40 conveniently applied and all seams may be carefully inspected during the stretching of the fur over the forms. Upon complete drying of the coat, the bottom is squared off and flat taped and the coat is ready for the finisher.

This method and apparatus eliminate ripping up the coat and making each part lie flat, save 45 fifty per cent of cutter's time, eliminate need of pattern, save seventy-five per cent of operator's time, save fifty per cent of nailing time, eliminate flat taping except at bottom of coat, an obviate 50 pounding of seams.

In view of the foregoing description taken in conjunction with the accompanying drawings, it is believed that a clear understanding of the construction, manner of use, and advantage of 55 the improved method and apparatus for reconstructing fur coats will be quite apparent to those experienced along this line. A more detailed description is accordingly deemed unnecessary.

It is to be understood, however, that even 60 though there is herein shown and described a preferred embodiment of the invention, various changes may be made without departing from the spirit and full intentment of the invention.

What is claimed is:

1. An apparatus for remodeling fur coats comprising a hollow body form having the outer surface of the wall thereof contoured to a size and shape corresponding to that of an ordinary clothed human body for placement of the body portion of a coat thereon and for shaping the coat to conform to the outer surface contour thereof, said body form having slots through the wall thereof extending from below the shoulder 70 area down the back of said form and increasing 75

in width as they extend downward, and flare forming members substantially V-shaped in cross section that diminish in size as they extend upwardly, said flare forming members being received in said slots and protruding into said hollow form and adapted to have material of the coat extended thereunder.

2. An apparatus for remodeling fur coats, constructed in accordance with claim 1, in combination with adjustable supporting means for the flare forming members that determine the depth of protrusion of the flare forming members into the hollow body form.

3. An apparatus for remodeling fur coats comprising a hollow body form having an opening therein of a size including substantially the entire back portion thereof, and a back section received in said opening and detachably connected to said body form for providing a back wall across said opening, said hollow body form and detachable back section having gradually contoured outer surfaces that align flush with one another for shaping a coat to the outer surface contours of the body form and the back section.

4. An apparatus for remodeling fur coats constructed in accordance with claim 3 in which said detachable back section has vertically arranged elongated slots through the wall thereof that decrease in width as they extend upwardly, and flare forming members received and detachably supported in said recesses and adapted to have material of the coat extended thereunder.

5. An apparatus for remodeling fur coats constructed in accordance with claim 3 in which said detachable back section has elongated slots through the wall thereof that are tapered in width as they extend from end to end, flare forming members extending through said slots and protruding into said hollow body form adapted to have material of the coat extended thereunder, and means for supporting said flare forming members in positions for adjusting the depth of protrusion thereof into the hollow body form.

6. A method of reconstructing fur coats to different sizes and styles without the use of patterns and having the joining edges of different skins and sections of coats blending together smoothly without taping of edges before sewing together and without pounding of seams of sewed edges, which consists of placing an unlined coat on a correctly styled and sized contoured form with the fur side next to the form and the skin side exposed, marking on the exposed skin side of the coat areas where pieces of skins are to be removed or inserted for closely approximating a fit of the coat to the form, removing the coat from the form, altering the coat according to the markings, wetting the skin side of the coat, replacing the coat on the form with the skin side exposed, stretching the coat tightly over the form, adding moisture to exposed skin areas where additional stretching and shrinking are desired, and allowing the coat to remain stretched on the form during drying and setting of the stretched and the shrunken skins and their stretched seams.

7. A method of reconstructing fur coats to different sizes and styles having flares or ripples without the use of patterns and having the joining edges of different skins and sections of coats blending together smoothly without taping of

edges before sewing together and without pounding of seams of sewed edges, which consists of placing an unlined coat on a correctly styled and sized contoured form with the fur side next to the form and with the skin side in a wet condition and exposed, forcing and retaining material of said coat into recesses in said form with kyles for producing flares, stretching the coat tightly over the form and under the kyles, adding moisture to exposed skin areas where additional stretching and shrinking are desired, and allowing the coat to remain stretched over the form and under the kyles during drying and setting of the stretched and the shrunken skins and their stitched seams.

8. An apparatus for remodeling fur coats comprising a form on which coats are fitted, stretched, and shrunk to size and shape, said form having the outermost surfaces thereof generally contoured to a size and shape corresponding to that of an ordinary clothed human body, said form also having recesses extending inwardly therein from said outermost contoured surfaces, and flare-shaping members received and supported in said recesses with material of the coat extending thereunder while other material of the coat is fitted over and shaped by said outermost contoured surfaces.

9. An apparatus for remodeling fur coats comprising a form on which coats are fitted, stretched, and shrunk to size and shape, said form having the outermost surfaces thereof generally contoured to a size and shape corresponding to that of an ordinary clothed human body, said form also having recesses extending inwardly and gradually rounding from the outermost contoured surfaces thereof, and tapered flare-shaping members received and supported in said recesses with material of the coat extending thereunder while other material of the coat is fitted over and shaped by said rounded surfaces of said recesses and said outermost contoured surfaces.

10. An apparatus for remodeling fur coats comprising a form on which coats are fitted, stretched, and shrunk to size and shape, said form having the outermost surfaces thereof generally contoured to a size and shape corresponding to that of an ordinary clothed human body, said form also having recesses extending inwardly and gradually rounding from the outermost contoured surfaces thereof, and flare-shaping members substantially V-shaped in cross section and gradually rounded together along the connecting side portions, said flare-shaping members being received and supported in said recesses with their rounded connecting portions projecting into said form and adapted to have material of the coat extended thereunder while other material of the coat is fitted over and shaped by said rounded surfaces of said recesses and said outermost contoured surfaces.
